UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

BOX-BLANK-STAPLING MACHINE.

Application filed April 22, 1922. Serial No. 555,938.

To all whom it may concern:

Be it known that I, EDWARD CRAIG, a citizen of the United States, and a resident of St. Joseph, Berrien County, Michigan, have 5 invented a certain new and useful Improvement in Box-Blank-Stapling Machines, of which the following is a specification.

This invention relates to wire bound box blank machinery of the kind in which the 10 staplers are capable of alternately driving long and short staples, inasmuch as the blanks made are each composed of alternate sections provided with cleats and intermediate sections which have no cleats. In a 15 machine of this character, the long staples are driven through the veneer or other sheet material into the cleats crosswise of the binding wires. Then the stapling mechanism is automatically controlled to stop the 20 driving of the long staples and to start the driving of the short staples, so that only short staples are driven in the next section, which has no cleats, these short staples being preferably just long enough to fasten 25 the binding wires to the veneer or the sheet material of this section, and to be properly clinched on the under surface of the blank. Furthermore, in the operation of a machine of this character, it becomes desirable to 30 prevent the driving of staples between blanks, of course, inasmuch as this would merely be a waste of staple wire. The invention relates, therefore, more particularly 35 to the automatic control of the stapling mechanism, which is desirable in a box blank machine of this character.

Generally stated, therefore, the object of the invention is to provide a novel and improved construction whereby the stapling 40 mechanism of a machine of this character is automatically controlled in a manner tending to insure more satisfactory results than heretofore; to provide an improved construction and arrangement whereby the action 45 of the stapling mechanism is automatically controlled by the operation of the ratchet feed mechanism by which the work is fed along to give the blank materials a step by step forward feeding motion below 50 the staplers; to provide an improved construction and arrangement whereby certain features of construction and combinations and methods of operation heretofore considered necessary are rendered unnecessary 55 and entirely dispensed with in the automatic

control of the action of the stapling mechanism to produce the desired result; and to provide certain details and features of construction and combinations tending to increase the general efficiency and the desirability 60 of a wire bound box blank machine of this particular character.

To these and other useful ends, the invention consists in the matters hereinafter set forth and claimed, and shown in the 65 accompanying drawings, in which,—

Fig. 1 is a rear end elevation of a wire bound box blank machine embodying the principles of the invention.

Fig. 2 is a vertical section on line 2—2 in 70 Fig. 1.

Fig. 3 is a vertical section on line 3—3 in Fig. 1.

Fig. 4 is an enlarged detail sectional view 75 showing certain elements of the mechanism for feeding the staple wire to the staplers.

Fig. 5 is a detail view of one of the cams of said wire feeding mechanism.

Fig. 6 is a similar view showing another 80 cam of said wire feeding mechanism.

Fig. 7 is a detail sectional view, on the same scale as Fig. 4, showing one of the wire feeding devices for feeding the staple wire to the staplers.

Fig. 8 is a side elevation of the mechanism 85 shown in Figs. 4 and 7 looking in a direction at right angles to the axes of the feed rolls.

Fig. 9 is an enlarged plan view of certain 90 portions of the machine, illustrating the arrangement whereby the traveling feed belt which feeds the blank materials forward serves also to automatically control the feeding mechanism which feeds the staple wire to the staplers.

Fig. 10 is a plan view, on a smaller scale, 95 of a portion of the feed belt by which the materials are caused to have an intermittent or step by step feeding motion through the machine, illustrating the way in which the feed dogs on said belt are provided with cams to control the action of the staplers.

Fig. 11 is a perspective of one of the box 100 blanks made by said machine.

Fig. 12 is a side elevation of one of the 105 cams or engaging portions of the two feed rolls which feed the relatively long lengths of wire to produce the relatively long staples.

As thus illustrated, the machine com- 110

prises a suitable body frame 1 adapted to support the various operative parts in suitably elevated positions. Parallel and longitudinally disposed guides 2 are provided to support the endless chains or feed belts 3 which are employed to move the blank materials intermittently along below the staplers to receive the staples which secure the binding wires 4 and 5 to the sheet material sections 6, 7, 8 and 9 as well as to the cleats 10 and 11, during the operation of making the blanks. The front end portions of the machine are not shown, but it will be understood that the machine is provided at both ends with sprocket wheels 12 to support the link belts 3, and it will also be understood that said belts travel in the direction indicated by the arrows shown in Figs. 2 and 10, so that the blanks are discharged at the rear end of the machine, after passing out from under the staplers. The two outside staplers 13 are double, so to speak, being constructed to drive either short staples or long staples, as fully shown and described in prior Patent No. 1,258,989, dated March 12, 1918. On the other hand, the two inside or intermediate staplers 14 are constructed to drive only relatively short staples. In this way, the long staples 15 are driven crosswise of the binding wires 4 and through the sheet material sections 6 and 8 into the cleats 10 and 11, thereby to secure the wires and sheets and cleats together. On the other hand, the short staples 16 are driven crosswise of the binding wires 4 and through the sheet material sections 7 and 9, to secure the wires to these sections, but these staples are clinched to the under side of the blank. In addition, short staples 17 are driven crosswise of the binding wires 5 through all four sections of the blank, and are clinched on the under side thereof, whereby the blank when made has four binding wires and four cleats, the sections 7 and 9 of the blank being cleatless, whereby the blank is adapted for use in making wire bound boxes by the method which involves the attaching of some of the cleats to the blank and the other cleats to the heads or end walls, as described in said prior patent, whereby it is not necessary to arrange the cleats end to end or in co-operative foldable relationship to each other, as it is sometimes called, in the manufacture of the blanks.

Now the automatic control of the staplers 13, to cause the alternate driving of long and short staples, and the cessation of all staple driving between blanks, is accomplished by controlling the feeding mechanism which feeds the staple wire to the staplers. As shown in Fig. 1, the staplers 13 have staple wire feeding devices 18 and 19, with tubes 20 and 21 leading therefrom to the staplers to feed the staple wire in the

desired manner. The feeding devices 18 are constructed to feed a relatively short length of wire, each time they are actuated, in order to produce the short staples previously mentioned; but, on the other hand, the feeding devices 19 are adapted to feed a longer length of wire in order to produce the relatively long staples previously mentioned. The feeding devices 22 are allotted to the staplers 14 and are adapted to feed a short length of wire to produce the relatively short staples 17 previously mentioned. The staplers 14, as previously indicated, do nothing but drive short staples and operate on each section of the blank, but the double staplers 13 alternatively drive long and short staples 15 and 16, as shown in Fig. 11, and the wire feeding devices thus provided for feeding the staple wire are automatically controlled by the step by step feeding motion of the feed belts 3 previously mentioned. Before describing this automatic control, the construction of each staple wire feeding device will be described and explained. Each wire feeding device comprises a relatively large feed roll 23, as shown in Fig. 7, and a relatively small idler feed roll 24, and the feed rolls 23 of the feeding devices 18 and 22 each have a relatively short cam or peripheral feeding portion 25, whereas these feed rolls 23 of the feeding devices 19 have relatively long cams or peripheral feeding portions 26, as shown in Fig. 12, thereby to insure the feeding of the relatively long and short lengths of wire previously explained. The feed rolls 23 are all mounted on the rotary transverse shaft 27 which is supported in bearings 28 at the opposite sides of the machine. On the other hand, the idler rolls 24 are supported on eccentrically mounted axles 29, the eccentric portions 30 being mounted in bracket bearings 31 which are supported on the transverse cross bar 32 of the machine. At the other side of the bracket bearing 31, the eccentric portion 30 is provided with a removable collar 33 provided with a flexible arm 34 having the end thereof provided with an engaging portion 35, in the manner shown. It will be seen that the rolls 23 and 29 are provided with gear teeth 36 by which they are geared together, whereby the staple wire 37, as shown in Fig. 7, is fed between the rolls in the desired manner. The wire 37 is first fed through a guide or tension device 38 before it enters between the feed rolls, so that the wire will be straightened before being fed into the tube 20 which leads to the stapler. The brackets 31 and the bearings 28 serve also to support a transverse shaft 39 upon which are mounted the cams 40, 41 and 42, the feeding devices 18 each having one of the cams 40, and the feeding devices 19 each having one of the cams 41, while the feeding devices 22 are

each provided with one of the cams 42, but each feeding device being provided with one of the engaging portions 35 to engage its allotted cam, and these engaging portions 35 being in absolute alignment transversely of the machine. Also, the said cams are mounted in their allotted feeding devices in the relative arrangement shown in Figs. 4, 5 and 6, where-
 5 by the engaging portions 43 of the cams 41 occupy positions opposite the spaces between the engaging portions 44 of the cams 40, and whereby the engaging portions 43 of the cams 42 are in transverse alignment
 10 with the engaging portions 43 and 44, so that the spaces 46 of the cam 42 are in transverse alignment with the spaces which would be observed between the portions 43 and 44 when the cams are viewed in the
 15 direction of their common axis. It will be seen that when the engaging portions 35 are being held by the engaging portions 44, the feed rolls 23 are then operative to co-
 20 operate with the feed rolls 24, as the latter are held in raised position, thus enabling the rotation of the shaft 27 to feed relatively short lengths of wire to the staplers 13 through the tubes 20 previously mentioned; but, on the other hand, when the engaging
 25 portions 35 of the feeding devices 19 are held in raised position by the engaging portions 43, the feeding devices 19 are then operative to feed relatively long lengths of wire through the tubes 21 to the staplers 13,
 30 and at such times the feeding devices 18 are out of commission, inasmuch as their engaging portions 35 are at such time resting in spaces between the engaging portions 44 of the cams 40 previously mentioned; and, of
 35 course, while the engaging portions 35 of the feeding devices 18 are in engagement with the engaging portions 44, so that the cam portions 25 are feeding relatively short lengths of wire, the feeding devices 19 are
 40 inoperative and do not feed any wire, for the reason that at such time their engaging portions 35 are resting in the spaces between the engaging portions 43; the two feeding devices of each double stapler 13
 45 thus alternating or taking turns, so to speak, in feeding wire to this stapler. The shaft 39 is intermittently rotated, as will hereinafter more fully appear, in the direction indicated by the arrow in Fig. 4, so that the said
 50 feeding devices 18 operate to feed relatively short lengths of wire necessary to produce the relatively short staples 16, and then the feeding devices 19 are automatically brought into operation, in place of the feeding devices 18, thereby to drive the relatively long staples 15, as shown in Fig. 11; for when the engaging portion 35 of any wire feeding device is down, and is not held in raised position by one of the four elevations or en-
 55 gaging portions of its allotted cam, this feeding device is inoperative to feed any wire, as at such time the feed roll 24 is slightly depressed and does not hold the wire against the larger or upper feed roll. The length of wire, or the length of feed of
 60 any feeding device, depends upon the length of the engaging portion 25 or 26 of the upper feed roll, and hence a forward movement is given the wire for each complete rotation of the upper feed roll 23 of each feeding device.
 The shaft 27 rotates continuously during the operation of the machine, but the shaft 39 operates intermittently. It is this shaft 39 and the cams thereon which control automatically the driving of the staples, for until this shaft 39 is given another partial rotation the driving of the staples will continue without any change in the character thereof.
 65 In the feeding devices 22 the engaging portions 35 rise and fall on the cams 42, and when these engaging portions 35 are in the notches or spaces 46 of said cams, the engaging portions 35 of all the other wire feeding devices are in the spaces between the cam portions 43 and 44, so that at such time all of the wire feeding devices are inoperative or out of commission, and no staple wire will be fed to any of the staplers. This total cessation of the feeding of staple wire to any of the staplers, at certain periods, is desirable, for example, while the spaces between sections are passing under the staplers, but the cessation of all staple driving between
 70 blanks is the more important, although it is desirable to accurately space the staples at opposite sides of the narrow gaps or joints formed between the four sections of the same blank. The shaft 39 is intermittently rotated by the ratchet wheel 47 rigidly secured to the shaft at one end thereof. The feed belts 3 are actuated intermittently by the ratchet wheel 48 on one end of the shaft 49 which supports the sprocket wheels 12, this ratchet feed mechanism for producing an intermittent or step by step feeding motion of the work serving to move the blank materials ahead after each staple driving operation.
 75 For this purpose, the oscillating or vibratory arm 50, which is mounted to swing on the shaft 49, is provided with a ratchet dog 51 to engage the ratchet wheel 48, and the upper end of said arm 50 is connected by an adjustable pitman 52 with the bell crank 53 which is pivoted at 54 upon the lower portion of the body frame 1 of the machine.
 80 The staplers are operated by cam devices 55, of a well known character, on the rotary shaft 56, and this shaft has an eccentric device 57 at one end thereof. A pitman 58 connects the eccentric device 57 with the shorter arm of the bell crank 53, and with this arrangement the ratchet wheel 48 is given a forward turn each time the staplers rise after driving staples in the blank mate-
 85
 90

 105
 110
 115
 120
 125
 130

rials; and, on the other hand, the feed dog 51 is retracted each time the staplers move downward to drive staples. The upper end of the arm 50 is provided with a pivoted rod 5 or long ratchet dog 59 for engaging the ratchet wheel 47, and it will be seen that the latter has twice as many teeth as the cam 42 previously mentioned and described. This ratchet dog or pawl 59 is controlled by a rotary shield 60 which is rotatably mounted on the shaft 39, and this shield 60 is automatically controlled by the feeding motion of one of the feed belts 3 previously mentioned. For this purpose, the feed dogs 61 on said 15 belt 3, which feed the materials forward below the staplers, have cams 62, and the other feed dogs 63 have similar cams 64, while the other feed dogs 65 have cams 66, all of said cams being arranged in position to engage 20 the roller 67 on the pivoted arm 68 which swings horizontally at one side of the machine. Said arm is connected by a rod 69 with the upper end of the bell crank 70, and the inner end of the latter is connected by a 25 rod 71 with the shield 60, whereby the latter is actuated each time one of said cams 62 or 64 or 66 engages the roller 67, in a manner that will be readily understood. A spring 72 is attached to the bell crank 70 to hold 30 the roller 67 normally in position to be engaged by the cams on the blanks or feed dogs of the belt 3, whereby the intermittent feeding motion of the blank materials is utilized to automatically and intermittently rotate the shaft 39 to change the positions of 35 the cams 40 and 41 and 42 previously described. The wire feed engaging portions 25 and 26 are preferably on segmental blocks 73 which are removable from the feed rolls 40 23, so that repairs or substitutions can be made, if necessary, to vary the length of feed, or for any other purpose.

Now assuming that the blank materials are in position on the machine, in the guides 45 2, and in engagement with the feed dogs 61, 63 and 65 on the feed belts 3, and the machine is started, the operation is as follows: Before the cam 66 strikes the roller 67, the engaging portions 35 of all the 50 staple wire feeding devices 18, 19 and 22 are down, so that all of the lower idler rolls 24 are slightly depressed, whereby no staples are being driven. However, as soon as the cam 66 does strike the roller 67, the 55 shield 60 is moved enough to allow the ratchet pawl 59 to engage the ratchet wheel 47, thus turning the shaft 39 enough to bring one of the cam engaging portions 43 of the devices 19 under their allotted engaging portions 35, thus throwing the feed 60 devices 19 into operation, because the lower feed rolls 24 thereof are brought up tight against the wire 37, and the latter is then fed forward by the peripheral engaging portions 65 26 of these two feed devices. As soon as

the roller 67 slips off from the cam 66, the shield or guard 60 prevents further operation of the ratchet 47 by the pawl 59, as the latter is thrown out of operative engagement with the ratchet, whereby the 70 shaft 39 stands still while the long staples 15 are being driven in the section 6 of the box blank. At the same time, of course, the cams 42 of the staple wire feeding devices 22 are in such position that their allotted engaging portions 35 are held up by projections or elevations 45 on these two cams, whereby the staples 17 are driven simultaneously with the staples 15 in the first 75 section 6 of the box blank. Of course, the work is being moved intermittently along, in the manner explained, and as soon as the cam 62 strikes the roll 67 the shield 60 is again moved to control the ratchet mechanism 47 and 59, but as this cam 62 is somewhat longer, it allows or permits a greater extent of operation of the ratchet mechanism, and a further rotation of the shaft 39, so that while all the portions 35 first drop into notches on their respective cams, the portions 35 of the feed devices 18 and 22 then immediately rise on the cam portions 44 and 45, in a manner that will be readily understood, leaving the portions 35 of the feeding devices 19 depressed in notches of their allotted cams; and this having taken place, it follows that the feed devices 18 and 22 are working to feed staple wire, while the feed devices 19 are out of commission and are not feeding any staple wire; and, consequently, the shaft 39 now standing still for a period of time, the staples 16 and 17 are now driven in the section 7 of the blank. The work having 80 been moved along step by step, until the cam 62 engages the roller 64, the shield or guard 60 is again actuated to control the ratchet mechanism 47 and 59, with the result, as will be obvious, that the feed devices 18 are rendered inoperative, and that the feed devices 19 and 22 are rendered operative, inasmuch as this cam 64 is as long as the cam 62, so that the feed devices 18 are rendered inoperative to feed any wire; and this having occurred, the staples 15 and 17 are now driven in the section 8 of the blank. Again the work moves forward, step by step, during the driving of the staples in the section 8, until finally the other cam 62 engages the roller 67, with the same result described in connection with the previous cam 62, inasmuch as it is now desired to drive only short staples 16 and 17 in the section 9 of the blank. During the 85 driving of these staples the work is being intermittently moved forward, each feed movement taking place just after the staplers have inserted four staples in a row across the blank, until finally the cam 66 at the rear end of the blank strikes the roll 67, 90

95

100

105

110

115

120

130

with the result that the shield 60 is moved to control the ratchet mechanism 47 and 59 just long enough to permit sufficient rotation of the shaft 39 to bring all of the 5 portions 35 of the various staple wire feeding devices into notches on their respective cams 40, 41 and 42, so that at such time none of the staple wire feed devices are feeding any wire, all of the lower feed rolls 10 24 being in their depressed positions. Therefore, while the space between this blank and the next one is moving along under the staplers no staples are being driven, but the driving of long staples 15 and short staples 15 in the first section of the next blank will be started as soon as another cam 66 strikes the roll 67 to again actuate the shield or guard 60 and thereby control the ratchet mechanism 47 and 59 in the manner previously described. It will also be seen that the automatic control thus exercised by the traveling motion of the blank materials not only serves to automatically change from long staples to short staples, and vice versa, 20 while the blank is traveling under the staplers, but also prevents driving of staples between blanks; and, in addition, the transition from long staples to short staples, or vice versa, is of such a character that no 25 staples will be driven between the sections of the same blank. The operations of the different parts are so timed that a notch 46 of each cam 42 is under the engaging portions 35 while the gap between two blanks 30 is passing under the staplers, and this is also true while the gap or joint between two sections of the same blank is passing under the staplers. As the cams 62 and 66 are on the blocks or feed dogs which carry the 35 materials forward, and inasmuch as these blocks are adjustable on the link belts 3 for blanks of different lengths, it follows that the automatic stapler control is automatically adjustable for blanks of different 40 lengths, the positioning of the blocks on the belts or chains serving automatically to readjust the automatic stapler control accordingly. The shaft 27 is rotating continuously, so that the various staple wire feeding 45 devices are all in motion, but no staple wire feed device can properly function to feed wire unless its allotted lower feed roll 24 is in raised position against the staple wire. Consequently, the cessation of the feeding 50 of the staple wire is not brought about by stopping the motion of the staple wire feeding devices, but merely by depressing the rolls 24 enough to cause slippage of the rolls on the wire, inasmuch as the rolls will not 55 have an effective grip on the staple wire 37, sufficient to feed it along in the desired manner; and this pressure of the rolls 24 against the staple wire can be varied or regulated by a slight adjustment of the collars 60 65 33 on the eccentric portions 30, it being observed that the rolls 24 are in effect mounted on cranks by which they are raised and lowered by the up and down motion of the portions 35 in the manner described. The portions 34 are preferably flexible, as stated, in order to afford a spring connection through which yielding pressure is communicated to the rolls 24 to hold them against the under side of the rolls 23, and to permit the rolls 24 to move down slightly as soon as the feeding portions 25 and 26 strike the staple wire. This is a very easy and quiet action, at the same time absolutely certain, so that the control of the feeding of the staple wire is of such a character that the changing from long to short staples, and vice versa, is accomplished in the desired manner, with certainty and without danger of breakage or disarrangement of any of the elements, and with comparatively simple means. The shaft 56 is connected to the shaft 27 by gearing 74, it will be seen, so that these two shafts rotate in opposite directions but at the same rate of speed. Of course, though, any suitable arrangement can be employed for rotating the shaft 27 in the desired manner. Also, of course, the means for clinching the short staples on the under side of the blank may be of any suitable character, such as the means shown and described in said prior patent, and no illustration or description thereof is necessary. The ratchet wheel 47, it will be seen, has any suitable or desired number of teeth, as for example, it may have sixteen teeth, as shown, so that the shaft 39 is given a one-sixteenth rotation each time this ratchet is operated by the long pawl 59, in the manner previously described. Thus, some of the cams on the chain or link belt control the shield 60 in a manner to permit two successive actuations of this ratchet device, as in changing from long to short staples, and vice versa, while other cams permit only one actuation of the ratchet, as is necessary in either starting or stopping the driving of staples by all of the staplers. Inasmuch as the feed roll mechanism for feeding the wire for the staples is operated continuously, by continuous rotation of the rolls of each device, it is obvious that the machine can be operated with considerable speed, without interfering with the proper feeding of the wire for the staples, for the continuous rotation of the feed rolls is converted into intermittent feeding motion on the part of the wire without any interruption of the smooth and steady rotation of the feed rolls. This intermittent feeding action, however, of the wire for the staples, is automatically controlled by the movement of one roll toward and away from the other, in the manner shown and described, so that the intermittent feeding of the wire is automatically stopped when it is necessary or desir- 70 75 80 85 90 95 100 105 110 115 120 125 130

able to discontinue the insertion of staples at any desired or predetermined point or points in the work passing under the staplers. Preferably, as shown, the mechanism for moving one roll toward and away from the other is automatically controlled by the forward feeding motion of the work feeding means by which the work is given an intermittent forward feeding motion below the staplers.

10. What I claim as my invention is:

1. In a wire bound box blank machine for making blanks by inserting relatively long staples in one or more sections of the blank, and relatively short staples in one or more sections thereof, the combination of one or more staple wire feeding devices to intermittently feed the wire for the long staples, one or more staple wire feeding devices to intermittently feed the 20 wire for the short staples, means for continuously operating all of said staple wire feeding devices, and instrumentalities to automatically control the grip of said devices on the wire, thereby to prevent the 25 feeding of wire for the long staples when it is desired to drive short staples, and to prevent the feeding of wire for short staples when it is desired to drive long staples, without interrupting the driving motion of 30 said devices.

2. A structure as specified in claim 1, said instrumentalities comprising means for feeding the work to advance the blank materials into position to receive the staples, and means automatically controlled by the feeding motion of the blank materials to cause said staple wire feeding devices to either grip or release the wire therein.

3. A structure as specified in claim 1, said 40 instrumentalities comprising an endless belt for feeding the blank materials, cams mounted on said belt, and means to engage said cams to control the functioning of said staple wire feeding devices.

4. A structure as specified in claim 1, said instrumentalities comprising a rotary shaft, means on said shaft to control the functioning of said staple wire feeding devices, a ratchet to intermittently rotate said shaft, 50 means for feeding the blank materials into position to receive the staples, and means whereby said ratchet is actuated by the actuation of said means for feeding the blank materials.

5. A structure as specified in claim 1, said instrumentalities comprising work positioning means for relatively positioning the blank materials, and cams carried by said work positioning means, together with 60 means to engage said cams to control the functioning of said staple wire feeding devices.

6. A structure as specified in claim 1, said 65 staple wire feeding devices each comprising a driven roll in an idler roll, the driven

roll having continuous rotation, and means controlled by said instrumentalities and thereby operative for moving the idler roll toward and away from the driven roll to start or stop the intermittent feeding of the 70 staple wire, without interrupting the intermittent feeding of the work or the continuous rotation of said driven roll.

7. A structure as specified in claim 1, said instrumentalities comprising means including a ratchet mechanism for causing step by step forward feeding movement of the blank materials into position to receive the staples, and means actuated by said ratchet mechanism to intermittently control the functioning of said staple wire feeding devices. 75

8. A structure as specified in claim 1, said instrumentalities comprising a ratchet mechanism, means operated thereby to control the functioning of said staple wire feeding devices, means to feed the blank materials forward into position to receive the staples, and means whereby the action of said ratchet mechanism is automatically controlled by the forward feeding motion of the blank 90 materials. 85

9. In a stapling machine, a staple wire intermittent feeding device therefor comprising a driven roll to rotate continuously, an idler roll to press the staple wire against the driven roll, mechanism to automatically move the idler roll toward and away from the driven roll to start or stop the intermittent feeding motion of the staple wire, thereby to prevent the driving of one or 100 more staples and thus automatically control the functioning of the feeding device without stopping the continuous rotation thereof, work feeding means, and instrumentalities controlled by the work feeding motion 105 to automatically control said mechanism, whereby the action of the stapling machine is automatically controlled by the feeding motion of the work.

10. In a wire bound box blank machine for making box blanks by stapling binding wires and cleats to sheet material, the combination of means for feeding the blank materials into position to receive the staples, with spaces between the blanks, staple wire 115 feeding devices for feeding the wire from which the staples are made, means for continuously operating said devices, and automatic instrumentalities controlled by the feeding motion of the blank materials to automatically control the functioning of said staple wire feeding devices without stopping the continuous actuation of said devices to prevent the driving of staples between blanks. 120

11. A structure as specified in claim 10, said instrumentalities comprising cams which move along with the blank materials, means to engage said cams, and means controlled thereby to cause said staple wire 130

feeding devices to either grip or release the staple wire, operative to release the staple wire while the space between the blanks is passing the stapling operation position.

5 12. A structure as specified in claim 10, said staple wire feeding devices comprising a continuously rotating driven roll, an idler roll, and means automatically controlled by said instrumentalities for moving the 10 idler roll toward and away from the driven roll to control the feeding action without stopping the rotation of the driven roll.

13. A structure as specified in claim 10, said instrumentalities being adapted and 15 operative to also prevent the driving of staples between sections of the same blank.

14. A structure as specified in claim 10, said instrumentalities comprising means to automatically cause said wire feeding devices to release their grip on the stapling wire therein while the space between the blanks is passing the stapling operation position.

15. A structure as specified in claim 1, 25 said means for continuously operating said feeding devices comprising an overhead shaft for the driving of the staples, and gearing from said shaft to said devices.

30 16. In a machine for feeding materials and inserting staples therein, thereby to produce wire bound box blanks, the combination of continuously driven feed rolls to feed the wire intermittently for the staples, mechanism for moving one roll toward and away from the other, without stopping the continuous rotary motion, thereby to govern the intermittent feeding of the wire, instrumentalities controlled by the feeding motion of the work to automatically control said 35 mechanism, thereby to prevent the driving of staples between blanks, and means for supplying binding wire to said blanks, in position to be fastened thereto by the staples,

whereby the action of said continuous rotation and the intermittent feeding motion of 45 the staple wire are automatically controlled by the feeding motion of the work.

17. In a work feeding and stapling machine, for making wire bound box blanks, the combination of continuously driven feed 50 roll mechanism to feed the wire for the staples adapted by continuous rotation to feed the wire intermittently, instrumentalities controlled by the feeding motion of the work to automatically control the action of 55 said continuous rotation on the wire, without stopping the rotary motion, thereby to prevent the driving of staples between blanks, and means for supplying binding wire to 60 said blanks, in position to be fastened thereto by the staples, whereby the feeding motion of the staple wire is automatically controlled by the feeding motion of the work.

18. In a stapling machine, a stapler, work feeding mechanism for feeding work beneath the stapler, continuously driven feed rolls for feeding wire to the stapler, mechanism for moving one roll toward and away from the other without stopping the constant rotary motion whereby to govern the 70 intermittent feeding of the wire, and instrumentalities actuated by said work feeding mechanism to automatically control said last named mechanism.

19. In a stapling machine, a stapler, work 75 feeding mechanism for feeding work beneath the stapler, continuously driven feed roll mechanism to feed wire to the stapler adapted by continuous rotation to feed wire intermittently, and instrumentalities actuated by the work feeding means to automatically control the action of said last named mechanism without stopping the constant rotary motion thereof.

EDWARD CRAIG.
